CLAIM

The ornamental design for a combined container and applicator for sun lotion or the like, as shown.

DESCRIPTION

FIG. 1 is a side elevational view of a combined container and applicator for sun lotion or the like showing my new design;

FIG. 2 is a view looking from the right of FIG. 1;

FIG. 3 is a top plan view;

FIG. 4 is a view looking from the left of FIG. 1;

FIG. 5 is a bottom plan view; and

FIG. 6 is a view showing the side opposite that seen in FIG. 1 with the cap portion removed.
